The ornamental design for a display screen with animated graphical user interface, as shown and described.

DESCRIPTION

FIG. 1 is a front view of a display screen with animated graphical user interface showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof; and,

FIG. 14 is the fourteenth image thereof.

The appearance of the animated image sequentially transitions between the images shown in FIGS. 1-14. The process or period in which one image transitions to another forms no part of the claimed design.

In the drawings, the broken lines are for the purpose of illustrating portions of a display screen with animated graphical user interface and environmental structure that form no part of the claimed design.
